Application July 13, 1943, Serial No. 494,525

31 Claims. (Cl. 103—270)

This invention relates to injectors, and it has particular reference to the construction and operation of injectors of the non-lifting type for feeding water to steam boilers, especially the boilers of locomotives, whereby, by the actuation of a single control member, the control of admission of both steam and water to the injector, and the opening and closing adjustment of the overflow, may be accomplished.

The principal object of the invention is to provide an injector which will deliver water to the boiler at the highest suitable temperature without "breaking", and which enables the injector to be operated at its minimum delivery capacity most of the time, the injector being, however, of a maximum capacity in excess of the water consumption rate of the boiler which it serves.

This is accomplished by an automatic adjustment of conditions obtaining within the injector during operation, as will hereinafter be explained, whereby an economy in the consumption of heat, and concomitantly of fuel, and of water, is attained. Moreover, the boiler is not subjected to periodic introduction of large volumes of relatively cold water, and the head of steam is more easily maintained because the water may be fed into the boiler at a substantially uniform, predetermined temperature.

In accordance with one aspect of the principle of the invention, the injector is operated as of the fixed steam inlet, adjustable water inlet type, and as the combining chamber pressure is a determinable related function of the delivery temperature, and the volume of water admitted to the injector affects the delivery temperature, and the feed of steam remains constant, the pressure in the combining chamber may be utilized to control the feed of water to the injector to thereby maintain the temperature of the water at delivery within a range not exceeding a predetermined practical maximum.

In another embodiment, utilizing the relation of functions referred to, the injector may be operated as of adjustable steam inlet, automatic water inlet, type, wherein the temperature of the water at delivery is maintained substantially constant and the delivery volume is varied by control of the steam.

The invention comprises a mode of operation, and mechanism related thereto, whereby the objects and principles of the invention may be most effectively and conveniently accomplished, including steam control valve means and means functioning automatically in response to operation of such steam control valve means for start-

ing the injector and for insuring its continued operation in accordance with predetermined requirements, all as will be explained hereinafter more fully and finally claimed.

6 In the accompanying drawings illustrating the invention, in the several figures of which like parts are similarly designated,

Fig. 1 is a schematic sectional side elevation of an injector and control means associated therewith embodying the principle of the invention in a preferred form.

Fig. 2 is an enlarged sectional side elevation of a check valve employed in the control means.

Fig. 3 is a graph showing operating characteristics of injectors in accordance with the embodiments of the invention, and

Fig. 4 is a view similar to Fig. 1, but on a smaller scale, illustrating a modification in which independent inlets are provided for steam admitted to the forcing steam nozzle and lifting steam nozzle of the injector, respectively, and whereby an adjustable steam inlet, automatic water inlet, injector is provided, in which the delivery temperature of the water may be maintained substantially constant.

Referring to Figs. 1 and 2, it will be understood that the injector has a body 1 of conventional form having the customary set of tubes (not shown), and it is provided with a steam passage 30 2, a water inlet 3 leading to a water passage 4, a delivery 5 leading to the boiler, and an overflow 6 opening into the body at 7.

To insure efficient operation, the conduit leading to the water inlet 3 will preferably be provided with a check valve to prevent back flow toward the tank, and this valve may have the usual orifice for conducting steam to prevent freezing of the water in cold weather.

As is customary in injectors of this type, the 40 delivery 5 leads to the delivery chamber in the lower end 8 of the injector body, and the overflow 6—7 communicates with the combining chamber located in the mid-portion 9 of the body.

Located preferably within the locomotive cab 45 within easy reach of the engineman, is the steam throttle valve having a body 10 piped by suitable connections (not shown) to the steam passage 2 of the injector body, so that steam entering the steam inlet 11 and controlled by the throttle valve 50 may be conducted to the steam passage 2. The steam valve comprises a main valve disk 12 seating upon a removable seat-piece 13, and having an apertured shell 14 enclosing an auxiliary or primer valve disk 15 having a limited axial movement within the shell 14 under the influence of a

valve stem 16, and adapted at the limits of such movement to carry with it into seated and unseated position the shell 14 with its main valve disk 12, as will be explained more fully hereinafter.

The stem 16 passes through an appropriate packing gland 17 and is connected for axial movement by a link 18 with the yoke arms 19 of a control lever or handle 20 pivoted at 21 in bearing elements 22 offstanding from the valve body. The link 18 is slotted at 18' to provide a lost motion connection which will be explained later.

The bearing sleeve 23 of the lever 20 is provided with a cam projection 24 adapted, in certain positions of the lever 20, and hence of the steam valve means 12-15, to cooperatively engage, and depress to open position, the stem 25 of a spring-seated control valve 26 to which steam is conducted from the valve body 10 through a passage 27.

It will be noted that the operation of the valves 12, 15 and 26 is thus responsive to movement of the lever 20 upon its pivot 21, and that there are four critical positions of the lever to which operation of the injector is in turn responsive, as indicated by the lines A, B, C and D, Fig. 1, as will appear hereinafter in the description of the operation of the injector. It will be noted, also, that valve-opening movement of the lever 20 is limited by cooperating stops 28 and 29 carried by the brackets 22 and lever 20, respectively.

The overflow passage 1 is provided with an automatic overflow valve comprising a body 30 having a main valve disk 31 seating at 32 in the body 30 and biased to closed position by a spring 33, and an auxiliary valve disk 34 seating within the disk 31 at 35 and biased to closed position by a spring 36. Opening and closing movement of the valve disks 31 and 34 is guided by a spider 37 on the main disk 31 and a stem 38 carried by the body cap 39, and it will be apparent from the construction illustrated that a limited opening movement of the valve disk 34 is possible before the flange 40 of its hollow stem picks up the cooperating abutment member 41 of the cage 42 of the main disc 31 to impart to it desired opening movement.

Opening of the overflow valve by unseating of the disks 31 and 34 is accomplished by the rod 43 of a piston 44 working in a cylinder 45, the piston and cylinder being provided with ports 46, 46a and 46b. Steam is admitted to this cylinder 45 beneath the piston 44 through a piped connection 47 to the outlet port 48 of the valve 26, as will later appear.

The water valve is similar in construction to the overflow valve, and includes a main valve disk 49, and an auxiliary valve disk 50 biased to its seat in the main disk by a seating spring 50'. The main disk may be held to seated position, and its opening movement limited, by a manually adjustable screw threaded stem member 51 carrying an abutment 51'.

Opening movement is imparted to the auxiliary valve disk 50 and therethrough to the main valve disk 49 by the rod 52 of a piston 53 working in a cylinder 54 provided with relief ports or vents 55, under the influence of pressure fluid admitted to the cylinder 54 beneath the piston 53 through a piped connection 56 to the injector body in the zone of the combining chamber. This piped connection 56 includes a check valve 57 the disk 58 of which is provided with a leak-

age port 59 (Fig. 2) for a purpose hereinafter appearing. The piped connection 56 is also in communication with the piped connection 47 by way of a check valve 60 and branch pipe 60'. The check valves 57 and 60 open in the direction of the arrows appearing upon them.

The operation of this embodiment of the invention (Figs. 1 and 2) is substantially as follows: As hereinbefore stated, there are four critical positions, A, B, C and D, of the lever 20, to which operation of the injector is particularly responsive. When the lever 20 is in the position A, as shown in Fig. 1, all of the injector valves 31, 34, 49 and 50 and the steam throttle and control valves 12, 15 and 26, are closed and the injector is out of operation. With the lever 20 in position B, the control valve 26 is opened but the steam throttle valve 12-15 remains closed due to lost motion afforded by the slot 18'. When lever 20 is in position C, control valve 26 is still open and primer disk 15 is full open and in position to pick up and open main disk 12. With lever 20 in position D, control valve 26 is closed and 12 and 15 are in full open position.

Hence when the lever is in position B, the injector is not functioning, but steam passing control valve 26 fills the pipe connections 47 and 56 and thus causes the pistons 44 and 53 in cylinders 45 and 54, through their rods 43 and 52, to open overflow valves 34-32 and water valves 50-49. Thus the injector body is permitted to fill with water which spills at overflow 6.

Upon movement, now, of the lever 20 to position C, control valve 26 still being held open and throttle valve 12-15 being partially open, the injector will begin to function. Also, as check valve 57 closes against steam flowing into pipe connection 56 from 47 through check valve 60, no steam can flow to the combining chamber 9 of the injector body except through the leakage port 59 of disk 58 of this check valve 57, which port is preferably about $\frac{1}{2}$ " diameter.

In this it is to be assumed that water valve disk 49 is held seated by stem 51 but that the auxiliary water valve disk 50 is free to open under the influence of steam in cylinder 54 acting on piston 53.

When the lever 20 is moved from position C to position D, the throttle valve 12-15 is fully opened, control valve 26 is permitted to close under the influence of its spring, and leakage of steam through ports 46, 46a and 46b from cylinder 45 will permit overflow valve 31-34 to close.

With the water valve 49 manually adjusted by the means 51-51' for minimum grading, the injector is now in condition to function with full automatic control of the water inlet valve in the following manner: This auxiliary water valve having been held open by steam at boiler pressure, say 250#, acting on piston 53 in cylinder 54, it must, when steam is cut off from cylinder 54, try to establish itself at a running position by seeking to close under the influence of its seating spring 50'. In this it is aided by steam escaping through pipe connection 56 past the port 59 in the disk 58 of check valve 57 to the combining chamber 9 of the injector body, until the spring 50' balances the pressure in the combining chamber acting on piston 53 in cylinder 54.

In order to insure proper functioning of the injector, it is necessary to maintain a delivery temperature not above a predetermined maximum, say between 250° F. and 275° F., and as the

pressure in the combining chamber is a determinable related function of the delivery temperature, and the volume of water entering the injector affects the delivery temperature, and the feed of steam remains constant, the pressure in the combining chamber may be utilized to control the feed of water, to thereby prevent the delivery temperature from rising above the predetermined maximum.

Hence, rise and fall of pressure in the combining chamber will be reflected in opening and closing movement of the valve disk 50 under the influence of the pressure-responsive piston 53 and counteracting spring 50', the force exerted by the latter being of a predetermined appropriate value.

Reverting to the opening of the overflow valve 31—35 when the lever 20 is in position to open valve 26 and admit steam to pipe connection 47, it is apparent that the steam enters cylinder 45 below piston 44, and, as this piston has a greater effective area than auxiliary valve 34, it will be operative to raise the valve 34 against the pressure of spring 36 even though the pressure in the injector body surrounding the valve 34 is equal to that of the steam admitted below the piston 44. This results in venting the injector body to atmosphere through the overflow opening 6, and the overflow valve 31 can rise from its seat under the opening influence of the parts 40 and 41 carried by the hollow stem of the valve 34 and the cage of the valve 31, respectively.

If, running "closed overflow," with the water valve 49 closed, the injector "breaks," this water valve cannot open because the pressure in cylinder 54 below the piston 53 and that above the water valve 49 is the same and the water valve is biased to close by spring 50'. Thus, although pressure from the combining chamber may pass through check valve 57 and pipe connection 56 to cylinder 54, the water valve 50 will not open, and, even if the boiler check sticks shut so that water from the delivery 5 cannot enter the boiler, water and steam will not blow back through the injector into the water tank.

If, however, the injector "breaks" with the water valve 49 open, the balance of pressures will in no way be effective, but "blow-back" into the tank will be prevented by the check valve in the water line previously mentioned.

Also, due to the provision of check valve 60, pressure from the combining chamber cannot reach the cylinder 45 in which the overflow valve-operating piston 44 operates, and hence the overflow valve 31, which is subjected to injector body pressure from above and open to atmosphere below, will not open. Obviously, if check valve 60 were omitted, pressure from the combining chamber could pass through check valve 57 and the branch pipe 60' into connection 47, and thence to cylinder 45, and the overflow valve would be opened by piston 44 the effective area of which is greater than that of the auxiliary valve 34, as hereinbefore stated.

Referring to the graph, Fig. 3, taken in connection with the foregoing description, it will be seen that the injector provided with the control means of the invention may be graded by the engineman, by manual adjustment of the extent of opening movement of the main water valve 49, between maximum delivery of 10,000 gals. per hr. at 180° F. and 15" vac. in the combining chamber, to about 5,500 gals. per hr. at 270° F. and 20# pressure in the combining chamber.

When the injector is in normal operation, at delivery temperatures of 270° F. and less, the auxiliary valve 50 will be inoperative and all water will enter by way of valve 49. When, however, 5 delivery falls below 5,500 gals. per hr. and the temperature at delivery tends to rise above the practical 270° F. to 275° F. range, the auxiliary valve 50 will come into operation due to increased combining chamber pressure, as determined by 10 spring 50', and thereafter the delivery will be maintained at approximately the desired optimum of 5,500 gals. per hr. at 270° F. In considering the foregoing quantities and temperatures of delivery, it should be remembered that, as 15 already stated, the injector is operated upon the principle of fixed steam inlet, adjustable water inlet.

It has been found that, in accordance with the principle of the invention, an injector may be 20 provided with controls which will make possible the maintenance of a substantially constant delivery temperature, preferably below a predetermined maximum, with adjustable delivery volume.

This is done, in combination with automatic 25 control of the overflow valve and water valve, by providing for utilization of the steam for admission separately to the forcing steam nozzle and the lifting steam nozzle of the injector tubes. Such a modified arrangement is illustrated in 30 Fig. 4.

In this embodiment, the usual form of lifting steam nozzle is replaced by a mere shell 61 which acts more as a guide than an orifice, for the reason that it is not necessary that it have the 35 throttling effect of the customary lifting steam nozzle, as will later appear, and steam is conducted to it through the steam passage 2. The forcing steam nozzle 62 is of more conventional form, but instead of receiving steam by way of 40 the passage 2, as is customary, is provided with a separate steam passage 2' in axial alignment with it at the top of the injector body 1.

Steam for both the forcing nozzle 62 and lifting nozzle 61 is initially controlled by the main throttle valve 10 which is in the form hereinbefore 45 described, but an auxiliary control for the lifting steam is provided by means of a manually adjustable, automatically actuated, steam valve 63 interposed between the throttle valve 10 and the 50 steam passage 2 leading to the lifting steam nozzle 61. This valve 63 is shown as of globe-valve type and includes a valve disk 64 seating in the septum 65 and provided with a stem carrying a piston 66 working in a cylinder 67 which is connected by a branch 68 with the pipe connection 47 leading from the control valve 26. A manually 55 adjustable abutment member 69 limits the extent of opening of the disk 64 by coaction with the piston 66 carried by the disk.

A check valve 57' similar to the check valve 57 is interposed in the branch 68 for a purpose later explained.

The water valve 70 is fully automatic, and includes a valve disk 71 having a seat 72 adjacent 65 to the water passage 4 and guided by a lower stem 73 passing through a spider 74 in the valve body and an upper stem 75 telescoping within a downward extension 76 of a piston 77 working in a cylinder 78 at the top of the valve body. 70 The lower stem 73 of the disk 71 is normally engaged by the rod 79 of a piston 80 working in a cylinder 81 at the bottom of the valve body, in much the same manner as the arrangement disclosed in the embodiment of Fig. 1.

75 Steam is conducted from the control valve 26

to the cylinders 78 and 81 through branches 47a and 47b, respectively, of the pipe connection 47 leading from such control valve. The piston 80, valve disk 71 and piston 77 are successively of gradually increasing effective area.

The overflow valve 30 is preferably the same in construction as that described in the embodiment of Fig. 1, and steam reaches its cylinder 45 through a branch 47c of the pipe connection 47 leading from the control valve 26.

The set of combining and delivery tubes (not shown) of the injector are of conventional form and have the property of functioning either with the admission of steam through the forcing steam nozzle 62 alone, or with steam admitted through both the forcing steam nozzle and the lifting steam nozzle 61.

In order to have the injector function with the admission of forcing steam alone, it is necessary to regulate the admission of water through the water valve 70, and the embodiment of Fig. 4 embraces this principle.

The foregoing characteristics, and the fact that the overflow valve and the main steam throttle valve, and their adjuncts, are preferably the same as those of the embodiment of Fig. 1, should be kept in mind in connection with the following description of the operation of the modification illustrated in Fig. 4. Also the check valves 57 and 60 are the same as their counterparts in Fig. 1.

Running "closed overflow" with admission of steam to the forcing steam nozzle 62 only, it has been found possible to maintain the temperature of the water at delivery at a predetermined desired temperature, say 250° F., which is a practical operating temperature. By adding steam through the lifting steam nozzle 61 and adjusting the water valve 70 to suit this increase in steam admitted, it has been found that the water delivery capacity of the injector may be doubled while still maintaining the same delivery temperature, or the injector may be adjusted to any intermediate capacity while still holding the same delivery temperature. This characteristic of operation is indicated by the broken line in the graph, Fig. 8.

In starting the injector, the lever 20 is moved to position B, Fig. 1, the priming position, whereby the control valve 26 is opened but the throttle valve 12-15 remains closed. Steam flowing past the valve 26 through pipe connection 47 and branches 47c, 47b, 47a and 68 acts to open overflow valve 30 and water valve 70, loads piston 77 to cause it to engage stop shoulder 77' to thus restrict such opening of the water valve (extent of movement *a* being less than *b*), and loads the piston 66 of lifting steam valve 63 to hold the same closed.

Further opening movement of the lever 20 passes steam from the throttle valve 12-15 to the forcing steam nozzle 62, and when the throttle valve is in full open position and the control valve 26 has, therefore, closed, the steam in pipe connection 47 and its branches will leak out through ports 46, 46a and 46b of cylinder 45 and its piston 44, thus permitting the overflow valve to close and the lifting steam valve 63 to open to admit steam to the lifting steam nozzle 61, the opening movement of the valve 63 being retarded by leakage of the steam trapped in its cylinder 67 through the leakage port of the check valve 57', thus avoiding opening of the steam valve 64 prior to closing movement of the water valve 71 to its appropriate

governing position. Also, steam having been exhausted from cylinder 78, and steam trapped between the check valves 57 and 60 having leaked through the port 59 in disk 58 of valve 57 into the combining chamber of the injector, the water valve disk 71 will be permitted to float in its proper governing position responsive to pressure entering cylinder 81 from the combining chamber balanced by the spring which loads the valve disk 71. Thus, again reverting to the principle that the combining chamber pressure is a determinable related function of the delivery temperature, and that the volume of water admitted to the injector affects the delivery temperature, the feed of steam being constant, it has been determined not only that the combining chamber pressure may be utilized to control the water inlet valve to maintain the delivery temperature constant, but that as the combining chamber pressure is increased or decreased by increasing or decreasing the feed of steam to the lifting steam nozzle 61, the feed of water to and volume of delivery from the injector may be increased or decreased in response to such pressure changes, and the delivery temperature maintained substantially constant.

It should be borne in mind, in considering the operating characteristics of the injector in both of the forms disclosed, that the ranges of temperature, pressure and delivery volume are predicated upon what may be considered normal or standard inlet, or tank, water temperature.

Various changes and modifications are considered to be within the principle of the invention and the scope of the following claims.

What we claim is:

1. In injectors the bodies of which are provided with appropriate water tube means and steam nozzle means, and means including valves for controlling the admission of water and steam, respectively, means for controlling actuation of the water valve to open said water valve in response to actuation of the steam valve control means and during functioning of the injector to maintain said water valve in an open condition the effective extent of which is governed in response to pressure conditions obtaining within the injector body.

2. In injectors the bodies of which are provided with appropriate water tube means and steam nozzle means, and means including valves for controlling the admission of water and steam, respectively, means for controlling actuation of the water valve to automatically open said water valve in response to actuation of the steam valve control means and during functioning of the injector to maintain said water valve in an open condition the effective extent of which is automatically governed in response to pressure conditions obtaining within the injector body.

3. In injectors the bodies of which are provided with appropriate water tube means and steam nozzle means, and means including valves for controlling the admission of water and steam, respectively, and for controlling overflow, means for controlling actuation of the water valve, and means for controlling actuation of the overflow valve, said water valve controlling means and said overflow valve controlling means serving to open said water and overflow valves respectively in response to actuation of the steam valve control means, said water valve controlling means operating during functioning of the injector to maintain said water valve in an open condition the effective extent of which is governed in re-

sponse to pressure conditions obtaining within the injector body, said overflow valve actuating means operating to close the overflow valve when said steam admission valve is actuated to admit steam to the injector for full functioning.

4. In injectors the bodies of which are provided with appropriate water tube means and steam nozzle means, and means including valves for controlling the admission of water and steam, respectively, and for controlling overflow, means for controlling actuation of the water valve, and means for controlling actuation of the overflow valve, said water valve controlling means and said overflow valve controlling means serving to automatically open said water and overflow valves respectively in response to actuation of the steam valve control means, and said water valve controlling means operating during functioning of the injector to maintain said water valve in an open condition the effective extent of which is automatically governed in response to pressure conditions obtaining within the injector body, said overflow valve controlling means operating to automatically close the overflow valve when said steam admission valve is actuated to admit steam to the injector for full functioning.

5. In combination with an injector having a body provided with appropriate water tubes and steam nozzles, and means including fluid-pressure actuated valves for controlling the admission of water to the injector and for controlling overflow, respectively, and valve means for controlling admission of steam to said tubes and nozzles, a single means for effecting control of all of said valves.

6. In combination with an injector having a body provided with appropriate water tubes and steam nozzles, and means including valves for controlling the admission of water and steam to said tubes and nozzles, respectively, and for controlling overflow, a single means for effecting control of all of said valves, and means operative during functioning of the injector to maintain said water valve in an open condition the effective extent of which is governed in response to pressure conditions obtaining within the injector body.

7. In combination with an injector having a body provided with appropriate water tubes and steam nozzles and a combining chamber adjacent to certain of said tubes, and means including valves for controlling the admission of water and steam to said tubes and nozzles, respectively, and for controlling overflow, a single means for effecting control of all of said valves, and means operative during functioning of the injector to maintain said water valve in an open condition the effective extent of which is governed by pressure conditions obtaining within said combining chamber.

8. In combination with an injector having a body provided with appropriate water tubes and steam nozzles, and means including valves for controlling the admission of water and steam to said tubes and nozzles, respectively, and for controlling overflow, an operating member for opening and closing said steam valve, means including a control valve functioning in response to actuation of said steam valve operating member, and pressure responsive means operatively associated with said water valve and overflow valve, respectively, and in communication with said control valve to receive a pressure fluid controlled thereby, whereby upon actuation of said steam valve operating member, in starting the

injector, said control valve will be actuated to effect fluid pressure opening of said water valve and overflow valve, and after starting and during running of the injector said control valve will be actuated to interrupt flow of pressure fluid and permit closing of said overflow valve and running adjustment of said water valve.

9. In combination with an injector having a body provided with appropriate water tubes and steam nozzles, and means including valves for controlling the admission of water and steam to said tubes and nozzles, respectively, and for controlling overflow, an operating member for opening and closing said steam valve, means including a control valve functioning in response to actuation of said steam valve operating member, pressure responsive means operatively associated with said water valve and overflow valve, respectively, and in communication with said control valve to receive a pressure fluid controlled thereby, and means affording communication between the pressure responsive means associated with said water valve and a pressure zone within the injector body, whereby upon actuation of said steam valve operating member, in starting the injector, said control valve will be actuated to effect fluid pressure opening of said water valve and overflow valve, and after starting and during running of the injector said control valve will be actuated to interrupt flow of pressure fluid and permit closing of said overflow valve and running adjustment of said water valve under the influence of pressure conditions obtaining in said pressure zone.

35 10. In combination with an injector having a body provided with appropriate water tubes, a forcing steam nozzle, a lifting steam nozzle, and means including valves for controlling the admission of water and steam to said tubes and nozzles, respectively, and for controlling overflow, and a separate valve for controlling the admission of steam to said lifting steam nozzle, an operating member for opening and closing said first mentioned steam valve, means including a control valve functioning in response to actuation of said steam valve operating member, and pressure responsive means operatively associated with said water valve, overflow valve and lifting steam valve, respectively, and in communication with said control valve to receive a pressure fluid controlled thereby, whereby upon actuation of said steam valve operating member, in starting the injector, said control valve will be actuated to effect fluid pressure opening of said water valve and overflow valve, and closing of said lifting steam valve, and after starting and during running of the injector said control valve will be actuated to interrupt flow of fluid pressure and permit closing of said overflow valve, opening of said lifting steam valve, and running adjustment of said water valve.

11. In combination with an injector having a body provided with appropriate water tubes, a forcing steam nozzle, a lifting steam nozzle, and means including valves for controlling the admission of water and steam to said tubes and nozzles, respectively, and for controlling overflow, and a separate valve for controlling the admission of steam to said lifting steam nozzle, an operating member for opening and closing said first mentioned steam valve, means including a control valve functioning in response to actuation of said steam valve operating member, and pressure responsive means operatively associated with said water valve, overflow valve and lifting steam

valve, respectively, and in communication with said control valve to receive a pressure fluid controlled thereby, the pressure responsive means associated with said water valve comprising separate means including members having different effective pressure areas tending to exert forces for opening and closing movement, respectively, upon said valve, whereby upon actuation of said steam valve operating member, in starting the injector, said control valve will be actuated to effect fluid pressure opening of said water valve and overflow valve, and closing of said lifting steam valve, and after starting and during running of the injector said control valve will be actuated to interrupt flow of fluid pressure and permit closing of said overflow valve, opening of said lifting steam valve, and running adjustment of said water valve.

12. In combination with an injector having a body provided with appropriate water tubes, a forcing steam nozzle, a lifting steam nozzle, and means including valves for controlling the admission of water and steam to said tubes and nozzles, respectively, and for controlling overflow, and a separate valve for controlling the admission of steam to said lifting steam nozzle, an operating member for opening and closing said first mentioned steam valve, means including a control valve functioning in response to actuation of said steam valve operating member, pressure responsive means operatively associated with said water valve, overflow valve and lifting steam valve, respectively, and in communication with said control valve to receive a pressure fluid controlled thereby, and means affording communication between the pressure responsive means associated with said water valve and a pressure zone within said injector body, whereby upon actuation of said steam valve operating member, in starting the injector, said control valve will be actuated to effect fluid pressure opening of said water valve and overflow valve, and closing of said lifting steam valve, and after starting and during running of the injector said control valve will be actuated to interrupt flow of fluid pressure and permit closing of said overflow valve, opening of said lifting steam valve, and running adjustment of said water valve under the influence of pressure conditions obtaining within said pressure zone.

13. In combination with an injector having a body provided with appropriate water tubes, a combining chamber adjacent to certain of said water tubes, a forcing steam nozzle, a lifting steam nozzle, and means including valves for controlling the admission of water and steam to said tubes and nozzles, respectively, and for controlling overflow, and a separate valve for controlling the admission of steam to said lifting steam nozzle, an operating member for opening and closing said first mentioned steam valve, means including a control valve functioning in response to actuation of said steam valve operating member, pressure responsive means operatively associated with said water valve, overflow valve and lifting steam valve, respectively, and in communication with said control valve to receive a pressure fluid controlled thereby, and means affording communication between the pressure responsive means associated with the water valve and said combining chamber, whereby upon actuation of said steam valve operating member, in starting the injector, said control valve will be actuated to effect fluid pressure opening of said water valve and overflow valve, and closing of said lift-

ing steam valve, and after starting and during running of the injector said control valve will be actuated to interrupt flow of fluid pressure and permit closing of said overflow valve, opening of said lifting steam valve, and running adjustment of said water valve under the influence of pressure conditions obtaining within said combining chamber.

14. In combination with an injector having a body provided with appropriate water tubes and steam nozzles, and means including valves for controlling the admission of water and steam to said tubes and nozzles, respectively, and for controlling overflow, a single means for effecting control of all of said valves, means operative during functioning of the injector to maintain said water valve in an open condition the effective extent of which is governed in response to pressure conditions obtaining within the injector body, and means for manually adjusting the extent of opening of said water valve to thereby adjust the volume of delivery of the injector.

15. In combination with an injector having a body provided with appropriate water tubes, a forcing steam nozzle, a lifting steam nozzle, and means including valves for controlling the admission of water and steam to said tubes and nozzles, respectively, and for controlling overflow, and a separate valve for controlling the admission of steam to said lifting steam nozzle, an operating member for opening and closing said first mentioned steam valve, means including a control valve functioning in response to actuation of said steam valve operating member, pressure responsive means operatively associated with said water valve, overflow valve and lifting steam valve, respectively, and in communication with said control valve to receive a pressure fluid controlled thereby, whereby upon actuation of said steam valve operating member, in starting the injector, said control valve will be actuated to effect fluid pressure opening of said water valve and overflow valve, and closing of said lifting steam valve, and after starting and during running of the injector said control valve will be actuated to interrupt flow of fluid pressure and permit closing of said overflow valve, opening of said lifting steam valve, and running adjustment of said water valve, and means for manually adjusting the extent of opening of said lifting steam valve to thereby adjust the volume of delivery of the injector.

16. Control means for an injector having a body provided with appropriate water tubes and steam nozzles, and means including valves for controlling the admission of water and steam to said tubes and nozzles, respectively, and for controlling overflow, including pressure responsive means for moving the water valve and overflow valve to open condition, in starting the injector, means for controlling the supply of pressure fluid from a source thereof to said pressure responsive means, and a single member operable to control the valve for admission of steam to said steam nozzles and to actuate the means for controlling the supply of pressure fluid to said pressure responsive means.

17. Control means as claimed in claim 16, in which the means for controlling the supply of pressure fluid to said pressure responsive means includes a valve which opens and closes in response to predetermined positions of said steam valve controlling member in its movement to control the admission of steam to said nozzles.

18. Control means as claimed in claim 16, in

which the pressure responsive means associated with said water valve and overflow valve are operable in response to the pressure of steam supplied through said supply controlling means from the main source of steam supplied to the injector.

19. Control means as claimed in claim 16, in which the valve for admission of steam to the injector nozzles includes an auxiliary valve member directly moved to open and closed position in response to movement of said single control member, and a main valve member movable in response to movement of the auxiliary valve member but provided with a lost motion connection therewith, said means for controlling the supply of pressure fluid to said pressure responsive means being held by said single control member in open position while said main steam valve member is closed to thereby permit automatic starting adjustment of said overflow and water valves and while at the same time said auxiliary valve member is open, and being closed when said main valve member is open to permit closing of said overflow valve and automatic running adjustment of said water valve.

20. Control means for an injector having a body provided with appropriate water tubes and steam nozzles, and a combining chamber adjacent to certain of said water tubes, and means including valves for the admission of water and steam to said tubes and nozzles, respectively, and for controlling overflow, including pressure responsive means for moving the water valve and overflow valve to open condition, in starting the injector, means for controlling the supply of pressure fluid from a source thereof to said pressure responsive means, means of communication between the pressure responsive means of the water valve and said combining chamber, and a single member operable to control the valve for admission of steam to said steam nozzles and to actuate the means for controlling the supply of pressure fluid from said source to said pressure responsive means.

21. Control means as claimed in claim 20, in which the pressure fluid connection to the pressure responsive means of said overflow valve is branched to the pressure responsive means of said water valve through the means of communication thereof with said combining chamber, and means is interposed in said branch to prevent flow of pressure from said combining chamber to the pressure responsive means of said overflow valve.

22. Control means as claimed in claim 20, in which the pressure fluid connection to the pressure responsive means of said overflow valve is branched to the pressure responsive means of said water valve through the means of communication thereof with said combining chamber, and check valve means is interposed in said branch to prevent flow of pressure from said combining chamber to the pressure responsive means of said overflow valve.

23. Control means as claimed in claim 20, in which the means of communication between the pressure responsive means of the water valve and said combining chamber is provided with means to restrict back flow of pressure fluid from said pressure responsive means of the water valve to the combining chamber.

24. Control means as claimed in claim 20, in which the means of communication between the pressure responsive means of the water valve and said combining chamber is provided with check valve means to restrict back flow of pressure

fluid from said pressure responsive means of the water valve to the combining chamber.

25. Control means as claimed in claim 20, in which the means of communication between the pressure responsive means of the water valve and said combining chamber is provided with a check valve provided with a leakage port to restrict back flow of pressure fluid from said pressure responsive means of the water valve to the combining chamber.

26. Control means as claimed in claim 20, in which the pressure fluid connection to the pressure responsive means of said overflow valve is branched to the pressure responsive means of said water valve through the means of communication thereof with said combining chamber, and means is interposed in said branch to prevent flow of pressure from said combining chamber to the pressure responsive means of said overflow valve, and additional means is interposed in the means of communication between the pressure responsive means of the water valve and the combining chamber to restrict flow of pressure fluid from said source to said combining chamber.

27. Control means as claimed in claim 20, in which the pressure fluid connection to the pressure responsive means of said overflow valve is branched to the pressure responsive means of said water valve through the means of communication thereof with said combining chamber, and means is interposed in said branch to prevent flow of pressure from said combining chamber to the pressure responsive means of said overflow valve, and additional means is interposed in the means of communication between the pressure responsive means of the water valve and the combining chamber to restrict flow of pressure fluid from said source to said combining chamber, the second-named means comprising a check valve provided with a leakage port.

28. Control means for an injector having a body provided with water tubes, a forcing steam nozzle and a lifting steam nozzle, and means including valves for controlling the admission of water and steam to said tubes and nozzles, respectively, and a valve for additionally controlling admission of steam to said lifting steam nozzle, and an overflow valve, including pressure responsive means for moving the water valve and overflow valve to open condition and the lifting steam valve to closed position, in starting the injector, means for controlling the supply of pressure fluid from a source thereof to said pressure responsive means, and a single member operable to control the first-named valve for admission of steam to said nozzles and to actuate the means for controlling the supply of pressure fluid to said pressure responsive means.

29. Control means as claimed in claim 28, in which the pressure responsive means for said water valve includes a pressure responsive element serving, upon starting of the injector, to limit opening movement of the water valve.

30. In a steam operated injector adapted for efficient operation at a delivery temperature not exceeding a predetermined maximum, and in which the delivery temperature and the combining chamber pressure are, fundamentally, related functions, means for maintaining the delivery temperature substantially constant while varying the delivery volume, by varying the inlet of steam and controlling the inlet of water to the injector, including an adjustable steam valve and a water valve the extent of opening of which is determined by pressure responsive means, and means for

subjecting such pressure responsive means to pressure obtaining in the combining chamber.

31. In a steam operated injector adapted for efficient operation at a delivery temperature not exceeding a predetermined maximum, and in which the delivery temperature and the combining chamber pressure are, fundamentally, related functions, means for maintaining the delivery temperature substantially constant, and approximating the predetermined maximum, while vary-

ing the delivery volume, by varying the inlet of steam and controlling the inlet of water to the injector, including an adjustable steam valve and a water valve the extent of opening of which is determined by pressure responsive means, and means for subjecting such pressure responsive means to pressure obtaining in the combining chamber.
